CLOTHES PEG

Bror Olof Gabriel Andersson, Malmo, Sweden,
assignor to Firma Industrifondenhet Lennart Rydenfors, Malmo, Sweden, a corporation
of Sweden

Application February 4, 1949, Serial No. 74,615
In Sweden February 7, 1948

3 Claims. (Cl. 24—137)

1

As is well known clothes-pegs of the most customary type consist of two hingedly associated wooden peg halves held together by a coil spring of galvanized wire which is disposed between the peg halves in transverse recesses provided on the facing sides thereof and the ends of which are bent across the outer sides of the peg halves so as to press the latter together at the two ends thereof which are formed as clamping jaws.

Moreover, another type of clothes-pegs is known, which also consists of two hingedly associated peg halves held together by a substantially U-shaped resilient wire, but in which the arms of the wire extend, each in a longitudinal groove provided in a peg half, towards the clamping jaws which are pressed together due to the action of the resilient wire, while the intermediate portion of the wire, which connects the arms thereof, is disposed in recesses which are provided in the peg halves and which extend from the end of the peg remote from the jaws up to the hinge connection.

The present invention relates to a clothes-peg which constructionally differs from the above-mentioned types of clothes-pegs and which presents considerable advantages over the known pegs.

An object of the present invention is to provide a clothes-peg which, as compared with the hitherto known types of clothes-pegs, can be easily manufactured completely mechanically, i. e. a clothes-peg which advantageously permits not only the machining of its various parts but also the assembly thereof in machines, it being thus possible to manufacture the clothes-peg at extremely low costs.

Another object of the invention is to provide a clothes-peg in which the clothes do not easily come into contact with, or become soiled by, metal parts.

The clothes-peg according to the invention is also of the type comprising two hingedly associated peg halves, clamping jaws provided on said peg halves, and a resilient wire substantially of U-shape for holding the peg halves together, said peg halves having each a longitudinal groove on its outer side for receiving the arms of the resilient wire, which extend in said grooves towards the clamping jaws to press them together, but in the present peg the intermediate portion of said U-shaped resilient wire is bent first at right angles to the wire arms to snap into transverse grooves provided in the peg halves, and then, after a new bending, along the lateral outer surface of the peg to connect the two wire arms so

that the peg is held together at the hinge point.

An embodiment of the invention will be elucidated in the following description, reference being had to the accompanying drawing in which

5 Fig. 1 is a perspective view of a clothes-peg according to the invention.

Fig. 2 is a side view of the peg.

Fig. 3 is also a side view of the peg, the peg being turned through 90° in relation to Fig. 2.

10 Referring to the drawing, the clothes-peg consists of two peg halves 1 and 2 of wood or other suitable material, which are hingedly associated by means of a substantially U-shaped resilient wire 3, e. g. a piano wire. The arms of the resilient wire extend each along the outer side of a peg half towards the ends 5 of the peg halves serving as clamping jaws which are pressed together due to the action of the resilient wire. Each peg half is provided at its outer side with

15 a longitudinal groove or recess 6 for receiving the wire. The intermediate portion 7 of the resilient wire, connecting its arms, extends around one half of the peg from the outer side of the one peg half to the outer side of the other peg half and may lie preferably on the outer side of the two peg halves in transverse grooves 8 provided therein, which prevent the resilient wire from sliding in the longitudinal direction of the peg. When assembling the clothes-peg, the resilient wire is passed with its intermediate portion

20 7 first on to the peg halves held together and is pulled over the peg, which is preferably made somewhat tapered, from the jaws towards the other end of the peg until the intermediate portion 7 of the resilient wire snaps into the transverse groove 8 on the outer sides of the peg halves. This assembling operation may be effected by machines at a great speed and therefore also at low costs.

25 40 The grooves 8 for the intermediate portion 7 of the resilient wire are arranged at the point where the hinge connection between the peg halves is situated. This hinge connection may be formed e. g. by a transverse semi-circular tongue

45 9 on the one peg half 1 and by a corresponding recess 10 on the other peg half 2. The arms of the resilient wire may be given any suitable length and the wire may have any suitable thickness.

50 55 What I claim and desire to secure by Letters Patent is:

1. A clothes-peg comprising two hingedly associated peg halves, clamping jaws provided on said peg halves, and a resilient wire substantially of U-shape for holding the peg halves together,

said peg halves having each a longitudinal groove on its outer side for receiving the arms of the resilient wire, which extend in said grooves towards the clamping jaws to press them together, said peg halves each having a transverse groove on the outer side thereof, an intermediate portion of said U-shaped resilient wire being bent first at right angles to the wire arms to snap into said transverse grooves provided in the peg halves and being additionally bent at right angles to the first bend along the lateral outer surface of the peg to connect the two wire arms so that the peg is held together at the hinge point thereof.

2. A clothes-peg as claimed in claim 1 and wherein the arms of said U-shape wire extend straight from said intermediate portion to the free ends thereof.

3. A clothes-peg as claimed in claim 2, said longitudinal grooves extending to the free edge

of each said peg half adjacent said clamping jaws, whereby said wire is connectible to said clothes-peg by sliding said intermediate portion toward said transverse groove from the end having said jaws with the arms sliding in said longitudinal grooves until said intermediate portion enters said transverse groove and is seated therein.

BROR OLOF GABRIEL ANDERSSON.
